COMBINED BRACKET AND LATCH FOR
OVEN DOORS

Victor A. Benson, Santa Clara, Calif.

Application October 21, 1950, Serial No. 191,426

2 Claims. (Cl. 126—191)

1

This invention relates to brackets and latches and more particularly to a combined bracket and latch for an oven door.

The invention herein has been shown embodied in an oven door structure formed as a part of a barbecue fire box of either the permanent or portable type. The invention contemplates the provision of a bracket structure for a door hinged along its lowermost horizontal margin which bracket serves as a means for latching such door in closed, vertical, position.

Another object is to provide a novel latch for holding an oven door in closed condition but free to open when a predetermined pressure or pull is exerted upon such door.

Another object is to provide a door bracket arrangement for a door hinged along its lower edge which bracket effects an over center action when the door reaches a predetermined angular disposition relative to closed position to thereby urge such door into closed condition.

These and other objects of the present invention will become apparent in the following description when read in the light of the drawings in which:

Fig. 1 is a perspective view of a portable barbecue unit embodying the present invention.

Fig. 2 is a fragmentary enlarged vertical section through the portable barbecue unit shown in Fig. 1.

Fig. 3 is a cross section through a permanent barbecue pit embodying the present invention.

Referring to the drawings Fig. 1 illustrates a portable barbecue unit 10 comprising a rectangular frame 11 having legs 12. Secured to the legs 12 midway their ends are angle irons 13 to which are secured side and back walls 14, 15 and 16 in the form of panels 17. A front wall 18 has its lower edge 19 disposed substantially above the lower angle iron 13. An angle iron 13f is secured to the edge 19 to provide a lintel for a door frame 20, the sides of which frame are formed by the inturned flanges 12' of the legs 12.

The upper edges of the front, back and side walls are girded by angle irons 21 having their flanges 22 extending outwardly. The angle irons 21 are secured to the upper ends of the legs 12 and form a support for a fire box 23, the lower portion 24 of which is suspended above a floor 25 secured to the angle irons 13. Thus the area between the fire box 23 and the floor 25 constitutes an oven 26 which is heated by the coals burning in the fire box. However, it will be apparent that a source of heat may be provided beneath the floor 25 by any conventional burner, not shown.

The barbecue unit 10' shown in Fig. 3 is similar to that shown in Fig. 1 with the exception that its side walls 14', 15', 16' and 18' are permanently made out of brick or the like. The unit 10' in form is much like the portable structure 10 in that the fire box 23 is suspended from the upper edges of the front, back and side walls. The floor 25' in the unit 10' is disposed a substantial distance below the fire box 23 to provide an oven 26'. The front wall 18' of the unit 10' has an opening 30 therein in which an angle iron door frame 31 is set and secured in the conventional manner, the lower margin 32 of frame 31 being in alignment with the floor 25' so that access to the oven 26' is gained through the opening 30. This is substantially the same structure as shown in Figs. 1 and 2 wherein the inturned flanges 12' of legs 12 form the side margins of the door frame 20, the lower angle iron 13' being in alignment with the floor 25 and the angle iron 13f at the lower edge of wall 18 forms the lintel over the door opening 30.

The door and combined bracket and latch therefore is generally designated by reference numeral 35 in the drawings. It includes an angle iron mounting member 36 having one of its flanges 37 secured to the lowermost angle iron 13' or 32 as the case may be in Figs. 1, 2 and 3 of the drawings. The other flange 38 of the member 36 extends outwardly from the oven and has one wing 39 of a hinge 40 secured to its lower surface. The other wing 41 of the hinge 40 is secured to the front face of a door 42, the axis pin 43 of the hinge being so disposed relative to the end of the flange 38 of mounting member 36 that the door 42 will swing into parallelism with the front face of the oven.

The door 42 comprises a flat panel 44 of sheet metal having one of its edges 45 abutting the hub 46 of the hinge 40. The opposite edge 47 of panel 44 is bent at right angles to provide an inturned flange 48 on the inner face of the door 42. The side edges 49 and 50 of the panel 44 are similarly provided with inturned flanges 51 and 52, respectively. The depth of the inturned flanges 48, 51 and 52 are such as to engage the outer surface of the frame 20 or 31 around the opening 30 to the oven, the lower edges 53 and 54 of side flanges 51 and 52, respectively, engaging the horizontal flange 38 of the mounting member 36 to thus completely close the opening 30.

Each side of the door 42 is preferably provided with a combined bracket and latch 55 comprising a straight metal strap 56, and a vertical slot 57 formed in the respective inturned flange

12'-12" of the side margin of the frame 20 or 31, respectively. The strap 56 has an enlarged head 58 at one end and has its opposite end 59 extended through its respective slot 57 for pivotal connection, as at 60, to the inner face of the adjacent side flange 51 or 52. The pivotal connection 60 in each case is preferably at least two thirds the radial distance of the upper flange 43 of the door from the hinge 40. The slot 57, as best seen in Fig. 2, is disposed a slightly lesser distance from the hinge 40 than is the pivotal connection 60 so that when the door 42 is raised into a position beyond two thirds closed position (see dot-dash illustration) the floor 61 of the slot 57 will support the strap 56 in substantially horizontal disposition. Consequently, as the door 42 is moved further toward closed position the ends of the straps 56 within the oven become counterweights. In this manner the counterweight ends of the straps effect an over-center action relative to the floor 61 of the slots 57 and thereby tend to pull the door 42 from partially closed position toward fully closed position. In other words, the enlarged heads 58 of the straps and the greater portions of the straps 56 being extended within the oven in cantilever fashion act as counterweights opposing the tendency of the door to fall toward open position. The weight of the enlarged ends 58 of the straps 56 and the length of the inwardly extending portions thereof are calculated to cooperate with the floor 61 of the respective slots 57 to urge the door 42 into fully closed position.

When the door 42 is in fully closed position (dotted lines Fig. 2) it will be noted that the pivotal connection 60 of the straps 56 with the side flanges (51-52) of the door is slightly higher than the floor 61 of the slots 57. Thus the floors 61 of the slots serve as fulcrums cooperating with the counterweight ends of the straps to automatically effect a lever action in latching the door in fully closed position. However, any outside force such as manually pulling the door open or any undue pressure from within the oven, as by a minor explosion, will counteract the foregoing latching effect of the straps 56 to allow movement of the door 42 toward open position. This is important, especially in connection with ovens heated by natural gas wherein a safety factor is required to prevent destruction of the oven in the event of an explosion within the oven.

In addition to the foregoing latching effect of the straps 56 relative to the oven door, these straps simultaneously serve as hanger brackets for supporting the door 42 in a horizontal position when opened. In this connection the lengths of the straps which act as part of the counterweight are suitable to extend from the horizontally disposed door to the upright angle irons 12'-12" in which the slots 57 are formed. Moreover the enlarged ends 58 of the straps, which also act as part of the counterweight, serve as a stop adapted to abut against the inner surfaces of the angle irons 12'-12" in which the slots are formed. In the latter connection the enlarged ends 58 of the straps 56 are each provided with an abutting surface 62 adapted to engage the inner surface of the respective angle irons 12'-12" above the slot formed therein. In this manner the straps 56 serve as hanger brackets for the door 42.

In addition to the foregoing the straps 56 sliding in the slots 57 serve to guide the door 42

properly between open and closed position, thereby minimizing the possibility of the door becoming warped or buckled out of shape during movement between its two extreme positions.

5 While I have described the best mode of putting my invention into practice it will be apparent to those skilled in the art that the same is susceptible to variations, modifications and alterations without departing from the invention. I therefore 10 desire to avail myself of all variations, modifications and alterations as fairly come within the scope of the appended claims.

What I claim as new and desire to protect by Letters Patent is:

- 15 1. A door structure for a barbecue warming oven comprising an upright door frame, an outwardly extending hinge support element mounted along the lower edge of said frame, a door hinged along its lower edge to an outer portion of said hinge support element, and of a thickness to close against said frame, a combined bracket and latch for said door comprising a strap having a substantially straight lower edge and pivotally connected to said door a predetermined distance from its hinged lower edge, said strap extending through a slot formed in said door frame and having an enlarged end engageable with said frame to hold said door in open position, and a 20 fulcrum in said slot acting as a fulcrum to cooperate with said strap when said door is raised a predetermined distance toward its closed position to effect a counterweighted lever action by said strap, between said slot floor and said door for urging the latter toward closed position.
- 25 35 2. A door structure for a barbecue warming oven comprising a rectangular door frame having a slot in each side thereof, a door support flange mounted along the lower edge of said door frame to extend outwardly therefrom, a shallow pan shaped door hingedly mounted on the outer edge of said door support flange, said door pan being of a depth to close with its marginal edge in contact with the door frame, a door control strap pivotally mounted on each side of the door pan 40 and extending through one of said slots, the inner end of each strap being larger than the slot through which it extends to limit the opening movement of the door, and a floor in each slot comprising a sliding fulcrum over which the strap moves slidably in opening and closing said door, the slot floor being spaced inwardly a short distance relative to the length of the strap from the strap pivot when the door is in closed position, and at a height relative to the strap pivot to incline the strap downwardly when the door is in closed position to exert a counterweighted door closing lever action on the closed door.
